ELEVATOR-SIGNAL.

1,134,448.

Specification of Letters Patent.

Patented Apr. 6, 1915.

Application filed July 25, 1914. Serial No. 853,222.

To all whom it may concern:

Be it known that we, ROBERT H. GAYLORD, residing at Pasadena, and GUY B. CAPPs, residing at Los Angeles, in the county of 5 Los Angeles and State of California, citizens of the United States, have invented a new and useful Elevator-Signal, of which the following is a specification.

Our invention relates to that class of elevator signaling systems in which a signal is given in an elevator car, by the operation of some form of circuit closing devices, generally push buttons, placed at the various floor landings, and in which the car signal is so controlled by the movement of the car that it does not become operative until the car is within a definite distance, say about two floors, from the floor at which the signal originated. Such a signaling system is 10 shown in patent to James B. Smalley and Charles A. Reiners, dated July 24th, 1906, No. 826,752, and for the purpose of illustration we have shown our invention as applied in connection with a system such as disclosed in said patent, but it will be understood that the invention is applicable in connection with any signaling system in which the car signal is controlled by the position of the car and by circuit closers at the landings. In a signal system of this kind, it is 15 not advisable to set the mechanism so that the car signal will become operative in excess of one and three-quarter floors ahead of the floor the signal is given from, for the reason that if the signal were given two or 20 more floors ahead, the operator would not know which one of such floors the signal was coming from and confusion and loss of time would result. Take for example, a case 25 where the car signal is set to become operative two floors in advance, and assume that the car on its up trip has arrived at the second floor landing and the up push button is operated at the fourth floor. The car signal at once becomes operative and the operator knows that a passenger or passengers 30 wish to go up, but he does not know whether the signal is from the third floor, fourth floor, or both floors, as no means are provided in the car signal for distinguishing the calls. The operator must then so control his 35 car that he can stop at the third floor, and finding no passenger at this floor, he knows that the call originated from the fourth

floor. As a result there was a waste of time 55 at the third floor, and in case the car was stopped, a waste of energy as well. It is evident that setting the car signal in excess of two floor landings in advance would greatly add to the confusion. It is customary to overcome this difficulty by setting the car signal approximately one and three-quarter floors in advance of the floor the signal is given from, and to so adjust the mechanism that no signal can be given the 60 car, from the immediate floor in advance, while the car is traveling the last three-quarters of the aforesaid floor height. This one and three-quarters floor advance is at a 65 disadvantage in the operation of high speed elevators, on account of the difficulty of bringing the car to a stop, in so short a space of travel, on receiving a signal.

The principal object of this invention is to provide means whereby the operator can tell 75 at a glance, whether the signal received is from the floor farthest ahead, within the control range of the mechanism, or whether the signal is from a nearer floor, and a further object of the invention is to accomplish 80 this result with but a single indicator in operation at any one time.

Another object of the invention is to cause the car signal to be normally held in readiness to give an advance signal when it approaches say within two floors, of a landing calling for a stop, and to automatically change the car signal to a full stop signal when the car approaches within say one floor of such landing, and to maintain this 90 stop condition of the car signal as long as there is a calling landing within one floor height ahead of the car, so that if a number of consecutive landings call for stops, the stop signal will be maintained continuously 95 as such landings are successively approached, and the car signal will only change to its normal condition for receiving an advance signal, when it approaches a floor that does not call for a stop.

Referring to the accompanying drawings: Figure 1 is a plan view of the commutator for the signal circuits. Fig. 2 is a section on line x^2-x^2 in Fig. 1. Fig. 3 is a section on line x^3-x^3 in Fig. 1. Fig. 4 is a section 105 on line x^4-x^4 in Fig. 3. Fig. 5 is a diagram of the circuit connections. Fig. 6 is an elevation of the circuit closer for locking the

100.

calling circuit closed until the car is in position to receive the call. Fig. 7 is an elevation of a modified form of the car signal.

The commutator may be constructed substantially as shown in the patent above referred to, comprising, for example, a frame 1, having side plates 2 of insulating material, on which are supported contacts for cooperating with brushes mounted on frames 3, pivoted on arms 4' of a carrier 4, formed as a nut working on a screw 6. Said screw is driven by suitable means indicated at 7, connected to the elevator sheave, so that the carrier will be moved longitudinally along the screw, by rotation of the screw in the nut, in correspondence with the motion of the elevator car in which the signals are to be given. As screw 6 rotates, it tends to turn the carrier 4 one way or the other, according to the direction of rotation of the screw, such turning of the carrier being limited by engagement of an arm 5 on the carrier 4 with a guide means 8, so that when the screw is turning in either direction the carrier arms 4' will be tipped in that direction, lowering the brush frame 3 at one side and raising the brush frame 3 at the other side.

The fixed contacts on the plate 2 at one side of the device comprise a long metallic strip contact 10 and a series of short metallic contacts 11 adjacent thereto, these contacts serving for resetting the circuit closers hereinafter described, and a long metallic strip contact 12 and a series of short metallic contacts 13 adjacent thereto, serving for control of the car signal. A pair of brushes 14 mounted in a brush holder 15 on the frame 3 at one side of carrier 4 travel over the contacts 10 and 11 so as to make metallic connection therebetween when the carrier is tipped so as to lower these brushes; said brushes both traveling on the upper contact strip 10 when the carrier is tipped so as to raise these brushes. The frame 3 at this same side of carrier 4 also carries a brush holder 16 in which is mounted a pair of brushes 17, adapted to travel over the contact strip 12 and contacts 13 when the said frame is in lowered position, to make metallic connection between long contact strip 12 and each of the short contacts 13 successively, and said brushes being both adapted to travel on the upper contact strip 12 when the said frame 3 is in raised position. A pair of brushes 18 is supported in brush holder 16 in advance of the brushes 17, so that connection between contact strip 12 and any of the contacts 13 is made first by the brushes 18 and then by the brushes 17. The brushes 17 are electrically connected, for example, by the metal of brush holder 16, but brushes 18 are insulated from said brush holder by insulating bushings 19, and a resistance 20 is in-

cluded in a connection between these brushes 18, to provide for control of the preliminary signal, as hereinafter described. The several brushes 14, 17, 18, may be provided with springs 9 for maintaining contact thereof with the fixed contacts, insulating heads 9' being interposed between the brushes 18 and the spring therefor. Similar fixed contacts 10', 11', 12' and 13' are provided on the plates 2 on the other side of the device, cooperating with brushes 14', 17', 18' on the frame 3 at the other side of carrier 4, the brushes 14, 17, 18 being in operative position when the carrier is tipped in one direction and is traveling, say, forwardly on the screw, due to downward motion of the elevator, and the brushes 14', 17', 18', on the other side being in operative position when the carrier 4 is tipped in the opposite direction and is traveling backwardly, due to ascent of the elevator car. The up and down push buttons 21 and 22, for the different floors of the building, are shown as controlling the signal circuits indirectly, through circuit closers 23, provided with operating magnets 25 and with resetting magnets 26, as in the patent aforesaid, the circuit closers being formed as levers, normally held in raised open position by the armatures 27 of magnets 25 and falling to position to close contact with fixed contacts 24, when armatures 27 are released therefrom by energization of magnets 25. Levers 23 are formed as armatures for the respective resetting magnets 26, which reset them to normal position.

The car signal device shown in Fig. 5 comprises two electric lamps, which may be differently colored, for example, a green lamp 30 for a preliminary or advance signal, and a red lamp 31 for a stop signal and electromagnetically controlled means such as solenoid or magnet 32, having armature lever 32' co-operating with contacts 33 and 34, to switch one or the other of these lamps into circuit, according to the strength of the current passing to the signal device.

The circuit connections, as shown in Fig. 5 for a single elevator shaft, are as follows: From a battery or source 35 of low tension current, a wire 36 leads to push buttons 21 and 22. From the up buttons 21 branch circuit wires or lines 37 lead through the controlling magnets 25 for the up circuit closers, back to the other battery lead 38. From the down push buttons 22 branch circuit lines or wires 39 lead through the down control magnets 25 to a battery leads 38. From battery lead 36 a wire 42 leads through transfer switch 52 in the elevator car to wires 43, 43' leading respectively to longitudinal contacts 10 and 10' of the commutator, and from the contacts 11 and 11' of the commutator, branch circuit wires 41 and 41' lead through the resetting magnets

26 for the up and down circuit closers respectively, to wires 40 and 40' leading to the battery lead 38. The energizing circuit for the signal device may comprise leads 45
 5 and 46 connected to any suitable means for supplying lighting current, for example to a dynamo, 47, lead 45 being connected by wires 48 and 48' to the long contacts 12 and 12' of the commutator at the down and up
 10 sides respectively, and lead 46 being connected through wires 49 and 49' to the down and up circuit closers 23 from which the connection is continued by wires 51 and 51' to the respective contacts 13 and 13' at the
 15 down and up sides of the commutator.

In the patent above referred to there are shown other devices, such as floor signals and controlling circuits therefor, which are not herein shown, as they form no part of the present invention, and the parts of the commutator which control the circuits for such devices are also omitted.

The operation is as follows: Assuming that one of the down buttons 22 has been operated, so as to close the circuit of battery 35, current will flow from said battery through lead 36 to the down push button which has been operated, to the corresponding branch circuit wire 39, and magnet 25 therein, and back to battery 35 through lead 38. Magnet 25 then operates its armature 27 causing the circuit closer lever 23 to be released and to fall to position to close circuit connection from dynamo 47 through wires 46 and 49, to contact 13 of the commutator. As the elevator car ascends the brushes 17 and 18 are caused to traverse the contacts 12 and 13 so as to successively bring the car signal contact 12 into connection with the contacts 13 connected to the circuit closers, and when the brushes 18 make such a connection with the contact to which circuit connection has been previously made from the operated circuit closer 23 as above set forth, a preliminary signal circuit is established as follows: from current source 47 through lead 45 and wire 48 to contact 12 of the commutator through one of the brushes 18 resistance 20 and the other brush 18 to contact 13 thence through wire 51 to circuit closer 23 and by wire 46 back to the source 47. The current flowing in this circuit is insufficient to operate the switch solenoid 32 for the car signal, so that only the preliminary or advance signal lamp 30 is energized, giving a preliminary signal to the operator, this action taking place when the car is say two floors above the calling floor. As the car continues to descend, the brushes 17 pass on to the aforesaid contact 13 of the commutator, establishing a circuit independent of the resistance 20, the circuit being otherwise the same as above traced, and the current flowing therein being sufficient to energize the magnet or sole-

noid 32 and cause the armature 32' thereof to operate to shift the connection of the signal circuit from lamp 30 to the stop signal lamp 31, so as to notify the operator that the next floor requires a stop. As the car passes the floor, the brush 14 passes over the resetting contact 11, corresponding to that floor, and, assuming that the operator leaves the transfer button closed, current will flow from battery 35 through lead 38 wire 40, resetting magnet 26, contact 11, brushes 14, contact 10, and wire 42 back to the battery, the resetting magnet being thereby operated to release the circuit closer 23 and allow it to return to its normal open position. The operation for the up signals is the same as above described, the reversal of motion of the car when it begins to ascend, causing the screw 6 to turn in the reverse direction and the carrier 4 to tip the other way so as to move the up brushes 14 into the contact 10 and the brushes 17 and 18 onto the contact 12, in which position they are inoperative, and at the same time moving the brushes 17', 18' and 14' on the up side of the carrier, down into engagement with the selective contacts 11' and the resetting contacts 13' respectively; these brushes then moving back longitudinally over these contacts and over the contacts 10' and 12' so as to bring each of the circuit closers successively into connection with the car signal, so that if any circuit closer is closed by operation of the corresponding push button circuit, the car signal will be operated, and in this operation the resistance 20 will first be included in the signalling connection and then cut out, so as to give a preliminary, followed by a stop signal.

Any car-signal device may be used, capable of responding distinctively to currents of different strength in the signal circuit. For example, instead of the two lamps shown in Fig. 1, a single lamp may be used, the difference in luminosity of the lamp due to difference of current strength in the signal circuit, indicating the differentiation between preliminary and stop signals. Thus, by means of a switch 53, see Fig. 5, the signal switch magnet 32 may be open circuited, the car signal device then consisting only of a single lamp 30, operating as stated. Or, as shown in Fig. 7, the car signal device may consist of a single lamp 54 and a screen 55, provided with windows 56 and 57 of green and red glass respectively, said screen being operated by a magnet 58 acting on an armature 59 connected to the screen. Normally the green window 56 is in front of lamp 54, and when the lamp is energized by a relatively weak current in the car signal circuit, the screen is held in normal position by the action of a spring 60, and a green light, for an advance or preliminary signal is exhibited, but when a

stronger current passes in said circuit, the screen is moved by magnet 58, so that the red window is brought in front of lamp 54, giving a stop signal.

5. What we claim is:

1. In an elevator signaling system, the combination of a car signal device, floor circuit closers and means controlled by the said floor circuit closers and by the movement 10 of the car to operate said car signal device to first give a preliminary signal, and then, in the further movement of the car, to give a stop signal.

2. In an elevator signaling system, a car 15 signal device adapted to respond to currents of different strength to give distinctive preliminary and stop signals, an energizing circuit for said signal device, and means controlled by the movement of the elevator 20 car to control said circuit to send a current of definite strength through the car signal device to give a preliminary signal when the car reaches a certain point and to send a current of different strength through said 25 signal device, to give a stop signal when the car reaches another point.

3. In an elevator signaling system, a car 30 signal device, an energizing circuit provided with a plurality of branches, push buttons at different floors and means controlled thereby to control the respective branches, a circuit controlling means controlled by the movement of the elevator car and adapted to put the car signal device successively in 35 connection with said branch circuits, said circuit controlling means being provided with a resistance and with means for first including such resistance in the connection established to the car signal and to then 40 cut out such resistance, to give a preliminary signal and to respond to the current flowing through such circuit when such resistance is cut out to give a stop signal.

4. In an elevator signaling system, the 45 combination with a car signal device provided with means for distinctively indicating a stop signal and a preliminary signal, controlling circuits for said signal device including a plurality of push buttons, means controlled by the movement of an elevator 50 car for bringing said signal device successively under control of the respective controlling circuits, said car controlled means being provided with means for closing a circuit connection to control the signal device 55 to give a preliminary signal and to thereafter close a connection to the signal device to give a stop signal.

5. In an elevator signaling system, the combination of a car-operated circuit controlling means, provided with contacts for closing a stop signal circuit, and with contacts for closing a connection for giving a preliminary signal, and a car signal means 60 connected to said circuit controlling means 65 and responsive to closure of the preliminary signal contacts of the circuit controller to give a preliminary signal.

6. In an elevator signaling system, a car signal device, an energizing circuit therefor having a plurality of branches, circuit closers in the respective branches of said circuit, controlling circuits including push buttons and also including operating means for said circuit closers, a resistance, a car 70 operated circuit controlling means provided with contacts connected in the respective branch circuits aforesaid and adapted to put the car signal device successively in connection with the respective branch circuits first 75 through said resistance, and then independently of said resistance, to send successive current impulses of different strength through the car signal device, said car signal device being adapted to respond to such currents of 80 different strength to give distinctive preliminary and stop signals.

7. In an elevator signaling system, the combination with a plurality of circuit closers for different floors, of a car signal 85 device and a commutator operated by the movement of the car to put the car signal device successively under the control of different circuit closers, said car signal device being provided with means for giving distinctive preliminary and stop signals, and being normally in condition to receive a preliminary signal, and means controlled by the movement of the car and by said circuit closers to control said car signal device to 90 change it to condition for a stop signal whenever a circuit closer for the next floor ahead has been operated and to maintain it in such condition as the car successively approaches two consecutive floors for which 95 the circuit closers have been operated, so as to give a stop signal without giving a preliminary signal under such conditions.

In testimony whereof we have hereunto set our hands, at Los Angeles, California, 110 this 17th day of July 1914.
